[57] CLAIM

The ornamental design for a shower caddy, as shown and described.

DESCRIPTION

FIG. 1 is a perspective view of a shower caddy embodying our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a side elevational view thereof showing the side opposite to that which is shown in FIG. 1;

FIG. 7 is a perspective view of another embodiment of a shower caddy embodying our new design;

FIG. 8 is a front elevational view of the embodiment of FIG. 7;

FIG. 9 is a top plan view of the embodiment of FIG. 7;

FIG. 10 is a bottom plan view of the embodiment of FIG. 7; and,

FIG. 11 is a rear elevational view of the embodiment of FIG. 7.

The side elevational view of the embodiment of FIG. 7 is identical to that which is shown in FIG. 6.

FIG. 1

FIG. 2

FIG. 3

FIG. 4

FIG. 5

FIG. 6

FIG. 7

FIG. 8

FIG. 9

FIG. 10

FIG. 11
